(57) **CLAIM**

The ornamental design for a pair of lanyard buckle connectors, as shown and described.

DESCRIPTION

FIG. 1 is a perspective view of the pair of lanyard buckle connectors connecting a buckle to a lanyard and a spring clip.

FIG. 2 is an enlarged perspective view of the upper portion of the pair of lanyard buckle connectors of FIG. 1, shown separately for ease of illustration;

FIG. 3 is a right side elevational view of the connector of FIG. 2.

FIG. 4 is a left side elevational view of the connector of FIG. 2.

FIG. 5 is a front elevational view of the connector of FIG. 2.

FIG. 6 is a rear elevational view of the connector of FIG. 2.

FIG. 7 is a top view of the connector of FIG. 2.

FIG. 8 is a bottom view of the connector of FIG. 2.

FIG. 9 is an enlarged perspective view of the bottom portion of the pair of lanyard buckle connectors of FIG. 1, shown separately for ease of illustration;

FIG. 10 is a right side elevational view of the connector of FIG. 9.

FIG. 11 is a left side elevational view of the connector of FIG. 9.

FIG. 12 is a rear elevational view of the connector of FIG. 9.

FIG. 13 is a front elevational view of the connector of FIG. 9.

FIG. 14 is a top plan view of the connector of FIG. 9; and, FIG. 15 is a bottom plan view of the connector of FIG. 9. The broken line showing of the lanyard, buckle and spring clip is for illustrative purposes only and forms no part of the claimed design.
